UNITED STATES PATENT OFFICE

142,910

DESIGN FOR A DISPLAY REFRIGERATOR

Clifford B. Shreve, Niles, Mich., assignor to Tyler Fixture Corporation, Niles, Mich., a corporation of Michigan

Application June 25, 1945, Serial No. 120,329

Term of patent 14 years

(Cl. D80—11)

To all whom it may concern:

Be it known that I, Clifford B. Shreve, a citizen of the United States, residing at Niles, in the county of Berrien and State of Michigan, have invented a new, original, and ornamental Design for a Display Refrigerator, of which the following is a specification, reference being had to the accompanying drawing, forming part thereof.

Fig. 1 is a perspective view of the display refrigerator from the front, and

Fig. 2 is a like view from the rear thereof.

I claim:

The ornamental design for a display refrigerator, substantially as shown.

CLIFFORD B. SHREVE.
